UNITED STATES PATENT OFFICE.

GUS F. LENK, OF DALLAS, TEXAS.

VENT STRUCTURE FOR FURNACES.

Application filed September 29, 1923. Serial No. 665,616.

To all whom it may concern:

Be it known that I, Gus F. LENK, citizen of the United States of America, residing at Dallas, in the county of Dallas and 5 State of Texas, have invented certain new and useful Improvements in Vent Structures for Furnaces, of which the following is a specification.

This invention relates to new and useful 10 improvements in vent structures for furnaces.

In the operation of furnaces it is desired to conserve the heat and prevent as much as is possible, its dissipation by radiation and to this end insulation is inserted in the furnace walls. While this is effective, the temperature around the furnace is usually exceedingly high, according to the intensity of the fire.

20 The object of my invention is to vent the furnace walls by including a space over the fire arch and circulating air through said space.

25 A further object is to reduce the temperature around the furnace by carrying off the hot air through a vent opening in the furnace wall, through which vent outside air is drawn.

30 Another object is to discharge the circulatory air into the smoke stack, independently of the furnace gases, whereby circulation is promoted.

35 A particular object of the invention is to cool the working floor above the arch and also to cool the metal charging hoppers.

40 An advantage of the invention is that by utilizing the vertical flue passage and taking in the air from the furnace all the advantages of an artificial mechanical suction system are had without the expense of installation or operation thereof.

45 A construction designed to carry out the invention will be hereinafter described together with other features of the invention.

50 The invention will be more readily understood from a reading of the following specification and by reference to the accompanying drawings, in which an example of the invention is shown; and wherein:

55 Fig. 1 is a transverse sectional view of a furnace constructed in accordance with my invention,

Fig. 2 is a longitudinal sectional view of the same, and

55 Fig. 3 is a plan view, the roof being broken away to show the air chambers.

In the drawings the numeral 10 designates the base or bottom of an incinerator or furnace. A front wall 11 and a back wall 12 extend upwardly and are connected by side walls 13 and 14 respectively, all of which extend upwardly from the base. The front and rear walls are connected by an arch 15 of refractory material having therein charging openings 16. This arch also extends between the side walls and forms a burning chamber. Above the arch 15 is the usual floor 17 of the incinerator.

Adjacent the side wall 13 a fuel grate 18 extends rearwardly from the front wall 11. Along the inner side of said grate is built a baffle wall 19 which extends rearwardly from the front wall to about the center of the burning chamber. Between the baffle wall and the side wall 14 consumption grates 20 are provided. Ash pits 18' and 20' are provided under the grates 18 and 20 respectively.

In the lower forward portion of the burning chamber an arched opening 21 is provided, contiguous to the surface of the adjacent grate 20. The details of the burning chamber are not considered essential as the same is subject to considerable variation, however the side escape of the products of combustion or gases over the grates is important.

Contiguous to the side wall 14 is built an auxiliary combustion chamber formed by a floor 22, an outer wall 23, a front wall 11', a rear wall 12' and an arch 24. The combustion chamber is of course lined with refractory material. In the wall 12' is formed a vertical opening or flue entrance 25 which is considerably less in width than the chamber and has its upper end some distance below the arch 24.

The arch 15 is covered on its upper side with a layer 26 of suitable insulating material and the arch 24 likewise has a similar covering 27. Between the coverings and the roof or floor 17 is an air chamber 28. It is pointed out that this air chamber extends over the entire interior of the furnace.

In the right hand end (Fig. 3) of the front wall 11 and above the burning chamber I provide an air admitting-duct 29 and a similar duct 30 is provided in the front wall 11', which latter is in fact a continuation and part of the front wall 11. Air is admitted to the air chamber by these two ducts, and after circulating therein passes

out through ducts 31 and 32 respectively, in the front and side of the smoke stack 34. These ducts 31 and 32 connect with a vertical air passage 33 surrounding the flue 5 35.

It is customary with incinerators, to which this invention is particularly applicable, to extend the floor 17 to form a platform over the furnace room and onto which the vehicles 10 may drive to unload through the charging holes 16. By means of the ducts 29 and 30, which are immediately under the floor, the hot air from in front of the incinerator is carried off and a circulation set up which 15 promotes a lower temperature around the furnace. The air passing through the chamber 28 will keep the floor 17 cool and carry off the excess heat therefrom. This circulation will also cool the hopper lining 20 16' of the charging holes. An incinerator equipped with this air chamber will have a longer life and function more satisfactorily. It is obvious that the vertical passage 25 33 in the stack will cause a good circulation through the chamber 28.

Various changes in the arrangement and structure of the different elements as well as modifications and alterations, may be made within the scope of the appended 30 claims.

What I claim is:

1. In a furnace, the combination with a burning chamber having a fire arch covering its top, a floor above the arch, and a 35 stack having a central smoke conduit, of an air chamber extending over the arch between the chamber and the floor, said chamber having an air admitting opening in one end and an outlet at the opposite 40 end free from connection with the conduit of the stack.

2. In a furnace, the combination with a burning chamber having a fire arch covering its top, a combustion chamber connecting with the burning chamber and having an arch covering its top, of a floor above the 45 arches, air admitting ducts for the chamber above each arch, a vertical air passage in the stack of the furnace separate from the 50 smoke conduit thereof and ducts contiguous to the arches leading into said passage.

3. In a furnace, the combination of a burning chamber, having a fire arch at its top, a combustion chamber having an arch 55 at its top, a stack connected with the combustion chamber and having a vertical smoke conduit, and a floor above the arches, an air chamber extending over the entire interior of the furnace between the arches 60 and the floor and having an air admitting opening at one end and an air outlet at its opposite end, said outlet being free from connection with the conduit of the stack.

4. In a furnace, the combination of a burning chamber, having a fire arch at its top, a combustion chamber having an arch at its top, a stack connected with the combustion chamber having a vertical smoke conduit, a floor above the arches, an air chamber extending over the entire interior 65 of the furnace between the arches and the floor and having an air admitting opening at one end and an air outlet at its opposite end, and a vertical air passage in the stack 70 separate from the conduit with which the chamber outlet connects.

5. In a furnace, the combination of a burning chamber having a front wall and an arch at its top, a stack having a vertical smoke conduit, and a floor above the 75 arch, an air chamber between the arch and the floor, an air admitting duct in the front wall above the arch leading to the chamber, a vertical air passage in the stack separate from the conduit, and an air outlet duct 80 leading from the chamber to the air passage 85 of the stack.

6. In a furnace, the combination of a burning chamber having a front wall and an arch at its top, a combustion chamber 90 having a front wall and an arch at its top, a floor spaced above the arches, a stack connected with the combustion chamber and having a smoke conduit, an air chamber extending horizontally between the arches and 95 the floor, an air admitting duct in the front wall of the burning chamber between the arch and the floor, a second air admitting duct in the front wall of the combustion chamber between the arch thereof and the floor, both of said ducts leading to the air chamber, a pair of air outlet ducts leading 100 through the sides of the stack from the air chamber, and a vertical air passage in the stack separate from the conduit into which 105 said outlet ducts discharge.

7. In a furnace having a burning chamber with an air chamber above and separate from the burning chamber and a floor above the air chamber, said air chamber having an air inlet immediately under the floor and an outlet for creating a draft through the air chamber.

8. In a furnace having a burning chamber with an air chamber above and separate 115 from the burning chamber, a floor above the air chamber, and a stack having a smoke conduit connected with the burning chamber, the air chamber having an air inlet at one side and an air outlet at the other side 120 and being free from connection with the burning chamber or the smoke conduit of the stack.

In testimony whereof I affix my signature.

GUS F. LENK.
